GEORGE D. HAUSER, OF UTICA, NEW YORK, ASSIGNOR TO UTICA PRODUCTS, INC., OF
UTICA, NEW YORK, A CORPORATION OF NEW YORK

SHEET METAL CASING

Application filed August 24, 1929. Serial No. 388,193.

This invention relates to sheet metal casings and pertains more especially to a casing for enclosing furnaces, boilers and the like.

An object of this invention is a furnace casing having flat sides and a rectangular top provided with improved means for attaching together the sides and the top so that the casing may be quickly, inexpensively and easily assembled around a furnace without the use of any special tools and even though there be but small space around the furnace in which to work.

A furnace casing embodying the invention comprises rectangular front and back plates having their upper and side edges bent inwardly and provided with grooves along said edges, together with side plates having similar upper edges, the vertical edges of the side plates being received within the vertical grooves of the front and back plates. A two-piece top plate has its edges received in the top edge grooves of the front, back and side plates and the meeting edges of the two top pieces are formed with co-acting semi-spherical recesses to provide an aperture through which may extend the flue of the furnace. At each upper corner there is provided a substantially pyramidal member which is held in place by a bolt passing through a lug carried by the adjacent side plate. The casing above described may be easily and quickly assembled simply by introducing the edges of the side plates into the grooves provided on the front and back plates and the edges of the top plate into the grooves provided for that purpose along the upper inturned edges of the front, back and side plates, after which the corner pieces are bolted in place and serve to lock the various plates in their assembled relationship. The front and back plates may be formed in two sections having a tongue and groove connection which permits slight adjustment of the sections toward and away from each other. The casing thus is adjustable both as to width and depth to compensate for variations in boiler sizes and all the joints are tight and rattle proof. The front panel of the casing is easily removable to facilitate repairs to the boiler or furnace which it encloses.

Other objects, novel features and advantages of this invention will be apparent from the following specification and accompanying drawings, wherein:

Fig. 1 is a perspective view of a furnace 55 provided with a casing constructed in accordance with this invention.

Fig. 2 is an enlarged section on the line 2—2 of Fig. 1.

Fig. 3 is an enlarged section on the line 60 3—3 of Fig. 1.

Fig. 4 is a top perspective exploded view of the casing.

Fig. 5 is an enlarged perspective view of a corner. 65

Fig. 6 is a section on the line 6—6 of Fig. 5.

Fig. 7 is a perspective view of a corner clamping member.

Fig. 8 is a perspective view of a furnace 70 provided with a modified casing, and

Fig. 9 is a reduced section on the line 9—9 of Fig. 8, and

Fig. 10 is an enlarged detail section.

The casing 10 is made up of vertical rectangular front and back plates 11 and 12, respectively, and a pair of side plates 13 together with a top composed of plates 14 and 15. The top and vertical edges of the front and back plates 11 and 12 are turned inwardly and are doubled back as at 11a and 11c to strengthen the same. The upper edges of the side plates 13 are also bent inwardly and are similarly doubled back at 13a. Strips of metal 11b and 12b are welded to the under 75 faces of the inturned edges of the plates 11 and 12 and are provided with offset portions or lips which form horizontal grooves with the doubled back portion of these plates. The inturned vertical edges of the plates 11 and 12 are provided with corresponding strips 11d and 12d which form vertical grooves with the doubled-back edges of the plates. The side plates 13 are provided with similar strips 13b. One of the top plates, in this instance, the plate 15, is provided with a strip 15b which forms a groove with the edge of the plate. The plates 14 and 15 are provided with semi-circular opposed recesses 16 and 17, 80 95 the strip 15b being correspondingly recessed. 100

- Preferably the front and back plates 11 and 12 are formed in two sections meeting along a vertical seam, (see Figs. 8 and 9.) One of the adjacent edges of the sections of the plate 11 is offset as at 11e and the other edge has welded thereto a strip 11f to form a slot to receive the offset edge 11e. Likewise the sections of the rear plate are provided with an offset edge 12e and a welded strip 12f.
10. Each of the front and back plates is cut away at its upper corner, such cut-out being necessary to permit the turning in of the top and side edges. Each upper corner of the side plates is also slightly cut away to permit the upper edges to extend between the in-turned edges of the front and back plates. This leaves an open space at each corner, which is covered by a pyramidal-shaped corner member 18. Each corner member is held in place by a bolt 19 which is threaded into a lug 20 carried by the adjacent side plate 13.
15. In assembling the casing around the furnace or boiler, the top plates 14 and 15 may be arranged with the boiler flue located in the recesses 16 and 17 and the edge of the plate 14 received in the groove formed by the lip 11 with the edge of the plate 15. The back plate 12 may now be arranged with the back edges of the plates 14 and 15 received in the groove formed by the lip 12b and the edge of the plate. Next the side plates 13 may be arranged with their edges received in the grooves formed by the lips 12d and the in-turned vertical edges of the plate 12 and the side edges of the plates 14 and 15 received in the grooves formed by the lips 13b and the edges of the side plates. The two back corner members 18 may now be placed in position and the bolts 19 threaded into lugs 20. It is not essential that these corner members be put on at this time, although it probably is better to do so.
20. The assembly of the casing is now completed by arranging the front plate 11 with the vertical edges of the side plates 13 received in the grooves formed by the lips 11d and the vertical edges of the front plate and with the front edges of the plates 14 and 15 received in the groove formed by the lip 11b with the top edge of the front plate. The front corner members 18 are next placed in position and the corresponding bolts 19 threaded into lugs 20. The bolts 19 are now tightened up all around to bring the various plates into snug contact with each other.
25. The depth of the various grooves is sufficient to compensate for slight variations in the size of boiler casings with which it is intended to be used. Where the boiler is slightly oversized the edges of the various parts will not extend the full depth of the grooves, but in any event, the plates will be firmly held in assembled relationship by the curved members. With this arrangement a two direction adjustment of the casing is provided,

The sections of the front and back plates are movable slightly toward and away from each other while the front and back plates are also movable slightly toward and away from each other, thus permitting slight adjustment both as to depth and width of the casing. With this type of structure, the front plate may easily be removed to permit access to the boiler. It is necessary only to remove the front corner members 18 and withdraw the front plate.

It is of course understood that various modifications may be made in the structure above described, without in any way departing from the spirit of the invention as defined in the appended claims.

I claim:

1. A casing comprising front, back and side vertical plates and a top plate, said vertical plates having tongue and groove connection with each other and with the top plate, said connections permitting slight variation of the distance between said plates, a corner member fitting over each top corner, and means for attaching each corner member to one of said plates.

2. A casing comprising front, back and side vertical plates, a top plate, said vertical plates having tongue and groove connection with each other and with the top plate, said front and back plates being formed of two sections having tongue and groove connections, said connections permitting variation of the distance between the opposite plates, a corner member fitting over each top corner, and means for attaching each corner member to one of said plates.

3. A casing comprising front and back vertical plates of variable width, vertical side plates and a top plate, said vertical plates having tongue and groove connection with each other and with the top plate, said connections permitting slight variation of the distance between the opposite plates, a corner member fitting over each top corner, and means for attaching each corner member to one of the vertical plates.

4. A casing comprising sectional front and back plates of variable width and having their upper and side edges bent inwardly and provided with grooves, side plates having their upper edges bent inwardly and provided with grooves, the vertical edges of the side plates being received within the vertical grooves of the front and back plates, a top plate having its edges received in the horizontal grooves at the top edges of the front, back and side plates, a corner member fitting over each top corner, and means for attaching each corner member to one of said plates.

5. A casing comprising front and back plates having their upper and side edges bent inwardly and provided with lips forming grooves with said edges, side plates having their upper edges bent inwardly and pro-

vided with lips forming grooves with said edges, the vertical edges of the side plates being received within the vertical grooves of the front and back plates, a top plate having its edges received in the horizontal grooves at the top edges of the front, back and side plates, a substantially pyramidal corner member fitting over each top corner, and means for attaching each corner member to one of the vertical plates.

6 6. A casing comprising front and back plates having their upper and side edges bent inwardly, lips carried by said edges and forming horizontal and vertical grooves therewith, side plates having their upper edges bent inwardly, lips carried by said edges and forming horizontal grooves therewith, the vertical edges of the side plates being received within the vertical grooves of the front and back plates, a two-piece top plate having its edges received in the horizontal grooves at the top edges of the front, back and side plates, said piece having recesses along their meeting edges to provide 20 an aperture, a substantially pyramidal corner member fitting over each top corner, and means for attaching each corner member to one of the vertical plates.

7. A casing comprising front and back plates having their upper and side edges bent inwardly, lips carried by said edges and forming horizontal and vertical grooves therewith, side plates having their upper edges bent inwardly, lips carried by said edges and forming horizontal grooves therewith, the vertical edges of the side plates being received within the vertical grooves of the front and back plates, a two-piece top plate having its edges received in the horizontal grooves at 35 the top edges of the front, back and side plates, said piece having recesses along their meeting edges to provide an aperture, a lip carried by one of said pieces and forming a groove with the edge thereof within which 40 is received the edge of the other piece, a substantially pyramidal corner member fitting over each top corner, and means for attaching each corner member to one of the vertical plates.

50 8. A casing comprising front and back plates having their upper and side edges bent inwardly and provided with grooves, side plates having their upper edges bent inwardly and provided with grooves, the vertical 55 edges of the side plates being received within the vertical grooves of the front and back plates, a top plate having its edges received in the horizontal grooves at the top edges of the front, back and side plates, a substantially 60 pyramidal corner member fitting over each top corner, and means for attaching each corner member to one of the vertical plates.

9. A casing comprising front and back plates having their upper and side edges bent 65 inwardly and provided with grooves, side

plates having their upper edges bent inwardly and provided with grooves, the vertical edges of the side plates being received within the vertical grooves of the front and back plates, a top plate having its edges received in the horizontal grooves at the top edges of the front, back and side plates, a substantially pyramidal corner member fitting over each top corner, a lug fastened to each upper corner of each side plate, and means for 70 75 attaching each corner member to the corresponding lug.

10. A casing comprising a pair of plates each having one end and two side edges bent inwardly and provided with grooves along 80 said edges, a second pair of plates having their end edges bent inwardly and provided with grooves along said edges, the side edges of the second pair of plates being received within the side edge grooves of the first pair 85 of plates, an end plate having its edges received in the end edge grooves of both pairs of plates, a substantially pyramidal corner member fitting over each corner of said end plate, and means for attaching each corner 90 member of one of the remaining plates.

11. A casing comprising a pair of plates each having one end and two side edges bent inwardly and provided with grooves along 95 said edges, a second pair of plates having their end edges bent inwardly and provided with grooves along said edges, the side edges of the second pair of plates being received within the side edge grooves of the first pair of plates, an end plate having its edges received in the end edge grooves of both pairs of plates, a substantially pyramidal corner member fitting over each corner of said end plate, a lug fastened to each of two corners of 100 the plates of one pair, and means for attaching each corner member to the corresponding lug.

12. A casing comprising a pair of plates each having one end and two side edges bent inwardly and provided with grooves along 110 said edges, a second pair of plates having their end edges bent inwardly and provided with grooves along said edges, the side edges of the second pair of plates being received within the side edge grooves of the first pair 115 of plates, an end plate having its edges received in the end edge grooves of both pairs of plates, a substantially pyramidal corner member fitting over each corner of said end plate, a lug fastened to each of two corners 120 of the second pair of plates, and means for attaching each corner member to the corresponding lug.

In testimony whereof, I have signed my name to this specification.

GEORGE D. HAUSER.
